CLAIM

The ornamental design for a closure clip for bag of
comestibles or the like, as shown and described.

DESCRIPTION

FIG. 1 is a perspective view of a closure clip for bag of
comestibles or the like showing my new design;

FIG. 2 is a top plan view thereof, the bottom being a
mirror image;

FIG. 3 is right side elevational view thereof, the left
side being a mirror image;

FIG. 4 is a front elevational view thereof; and

FIG. 5 is a rear elevational view thereof.

FIG. 1

FIG. 2

FIG. 3

FIG. 4

FIG. 5
